UNITED STATES PATENT OFFICE.

JAMES P. CAULFIELD, OF BALTIMORE, MARYLAND.

PLAYER GRAND PIANO.

1,174,682.

Specification of Letters Patent.

Patented Mar. 7, 1916.

Application filed January 21, 1913. Serial No. 743,258.

To all whom it may concern:

Be it known that I, JAMES P. CAULFIELD, a citizen of the United States, residing at Baltimore, in the State of Maryland, have 5 invented certain new and useful Improvements in Player Grand Pianos, of which the following is a specification.

This invention relates to an improvement in cases for player pianos and has particular 10 reference to an improved construction of fall boards and desk.

One object of the invention is to provide an improved construction of case whereby the tracker and music roll holders may be 15 entirely concealed if desired during the operation of the keys by hand.

Another object is to provide an improved arrangement of fall board and desk that may readily be folded to conceal or expose 20 the tracker without requiring movement of the latter.

A further object of the invention is to provide an improved arrangement of spool boxes, fall-board and desk whereby access 25 to the boxes by movement of the fall-board and desk parts may be readily effected.

With these and other objects in view the accompanying drawings illustrate the invention wherein,

30 Figure 1, shows a vertical longitudinal cross-section through the case with the fall-board down and covering the keys,—the section being taken on the line 1—1 of Fig. 6. Fig. 2, illustrates a vertical cross-section 35 through the same parts but with the fall-board raised to expose the keys for hand operation,—this section being taken on the line 2—2 of Fig. 6. Fig. 3 shows a front elevation of about one half of a piano, 40 the fall-board being raised to expose the keys for hand operation. Fig. 3^a, illustrates a front elevation of substantially one-half of a piano, the fall-board being laid back on top of the desk to expose the tracker and

45 spool boxes. Fig. 4, illustrates a vertical cross-section through the case with the fall-board folded back,—the section being taken on the line 4—4 of Fig. 3. Fig. 5, also shows a vertical cross-section through the case and 50 spool boxes with the fall-board raised to expose the keys,—this section being taken on the line 5—5 of Fig. 3. Fig. 6, illustrates a top plan of a portion of the piano case showing the fall-board down over the keys. 55 Fig. 6^a, shows another top plan view of the

piano with the fall-board folded back to permit the music rack to be turned up. Fig. 7, shows a perspective detail of one of the side walls of the case and the hinge connection which carries the fall-board, and Fig. 8, 60 illustrates in perspective the hinge.

Referring to the drawing the numeral, 1, designates the key bottom, 2, the opposite side walls; 3, the key slip and 4, the keys. A plank, 5, extends horizontally between the 65 side walls to form a support for the metal frame, 6, in the usual manner. At the center or midway between the side walls the piano has an upper spool or roll box, 7, and a lower spool or roll box, 8, and the 70 tracker bar, 9, is rigidly secured in place between said upper and lower boxes. At each end of the roll boxes the front of the piano has vertical panel boards, 10, which 75 extend to the side walls, 2, and are rigidly secured in place. Wall strips, 11, are secured against the inner vertical sides of the two side walls, 2, and a plurality of supporting bars, 12, extend horizontally from one wall strip to the other to form supports to 80 sustain the horizontal desk board, 13. This desk-board has a cut-out portion which extends from the rear toward the front, as clearly shown in Fig. 6, and a music rack leaf, 14, has a hinge, 15, at its front edge and 85 fits into said cut-out so as to be hinged to the narrow horizontal front strip portions, 16, of the desk. A hinge strip, 17, is also pivoted to the hinge, 15, in front of the music rack leaf and said strip has position at the 90 center and directly over the upper music roll or spool box, 7. By reason of the hinging of strip, 17, the same may be turned up to almost entirely uncover the upper spool or roll box, 7, and permit ready access to the 95 latter during the insertion or removal of the music rolls.

By referring to Figs. 1, 6, 7, and 8, it will be noted that to the inner side of each side wall there is pivoted a hinge bar, 18, which 100 latter normally extends in a horizontal plane over the upper edge of the wall strip, 11, and over the front supporting bar, 12. The free end, 19, of these hinge bars is broadened in a vertical or crosswise direction and extends down slightly at the inner side of the side wall and in front of the upper edge of the panel board, 10. A horizontal cross-bar, 20, extends from one hinge bar, 18, to the other, and has its ends rigidly 110

connected to the free ends 19, of said hinge bars. Along the inner bottom edge this horizontal cross-bar is provided with a hinge, 21, and the upper horizontal edge of 5 a vertical cover-board, 22, is attached to said hinge and depends in front of the panel boards, 10. This vertical cover-board, 22, extends continuously from one side wall, 2, to the other and therefore depends in front 10 of the two panel boards, 10; also in front of the upper and lower spool or roll boxes, 7, and 8, and in front of the tracker bar, 9, as is shown in Figs. 1 and 5 of the drawings. Thus it will be seen that the vertical cover-board, 22, serves as a front cover by depending in front, to entirely conceal the spool boxes and tracker.

By referring to Fig. 1, of the drawing it will be seen that the lower horizontal edge of the vertical cover board, 22, is provided with a hinge, 23, and that a horizontal fall-board, 24, has its rear edge connected to said hinge so as to be pivotally carried by said vertical cover board. This fall board, 24, has a flange, 25, at its outer edge and when in the lowered position, as shown in Fig. 1, said flange, 25, rests upon the top edge of the key slip, 3. When the fall-board and its flange are in the lowered position they will entirely cover and conceal the keys, 4, as shown in Fig. 1, and in the left-hand portion of Fig. 6. The fall board, 24, and its flange, 25, however, by reason of the hinge, 23, may be swung up to expose 30 the keys for the hand operation, as shown in Fig. 5, at which time the flange, 25, will pass beneath the cross-bar, 20, and will remain under said bar during the operation of the piano by hand. The fall-board 24, when 40 raised, will have a backwardly-inclined position by reason of the forward location of the pintle of hinge 23, which may be sufficient in practice to maintain the fall-board up. This is immaterial however as the fall-board may be held up by any of the devices 45 well known to piano manufacturers. While in this hand-operating position, it will be noted (see Fig. 5) that both the fall board, 24, and vertical cover-board, 22, will entirely conceal the spool or roll boxes, 7, and, 50 8, and the tracker, 9. While the fall board is in this hand-operating position the music rack or leaf, 14, may readily be turned up on the hinge, 15, to support the music,—a strip, 26, being provided along the front edges of the narrow strip portions, 16, of the desk and also across the hinge strip, 17, to receive the lower edge of the music sheet or book.

55 When it is desired to automatically operate the piano the fall board, 24, will first be turned up with its flange, 25, beneath the cross-bar, 20, as in Fig. 5, then the lower horizontal edges of the boards, 22, and, 24, will be grasped by the hand, beneath the

hinge, 23, and pulled up. During this operation the hinge bar, 18, will come into play because the upward movement of boards, 22, and, 24, will impart a like movement to cross-bar, 20, and the free ends, 19, of the hinge bars which latter will be turned backward and reversed. This reversal of the hinge bars causes the cross-bar, 20, to also be reversed as it is swung back over the desk, 13, and music rack, 14, to the position shown in Fig. 2, and during this operation the cover boards, 22, and fall board, 24, will uncover the front of the spool boxes, 7, and, 8, and the tracker bar, 9. An inclined groove, 27, is provided in the upper side of each side wall strip, 11, as clearly shown in Figs. 1, 4, and 7 so that the hinge bar, 18, may seat therein and permit the bar, 20, to be lowered at the rear of the desk and music rack. After the bar, 20, and boards, 22, and, 24, have been turned back over the desk, the boards may then be swung down on the hinge, 21, and laid on top of the desk as shown in Figs. 3 and 4, thus leaving the spool or roll boxes and tracker exposed. To finally place the music rolls, the hinge strip, 17, may be temporarily swung up on the hinge, 15, during the placing of the roll and when the latter is in place the strip will be returned so as to 95 cover the upper side of roll box 7.

By means of the present invention a grand piano may be provided with player mechanism and the tracker and roll boxes entirely covered, protected and concealed when not in use as a player.

Having thus described my invention what I claim and desire to secure by Letters Patent is:—

1. A case for a player grand piano having 105 roll holders for the music rolls, a cover board movably sustained in front of said holders to conceal the same and a fall board for the keys,—said fall board being carried by the said cover board.

2. A case for player grand pianos having upper and lower roll holders for the music rolls, a board in front of said holders; means for sustaining said board to give it substantially a vertical movement in front of 115 the roll holders and a fall board for the keys, said fall board being carried by the said vertically-movable board.

3. A case for player grand pianos having upper and lower roll holders for the music 120 rolls, a board pivotally sustained in front of the roll holders so as to be moved upwardly and rearwardly to expose the holders and a fall board for the keys,—said fall board being carried by the pivotally-sustained board.

4. A case for player grand pianos having upper and lower roll holders for music rolls, a board pivotally sustained in a pendant position in front of the roll holders to 130

conceal the latter and a fall board pivotally connected to the said pendant board and foldable against the latter.

5. A case for player grand pianos having upper and lower roll holders for the music rolls, a desk above said holders; a board in front of the roll holders to conceal the latter; means for sustaining the board so the latter may be swung from in front 10 of the roll holders and moved over the desk and a fall board for the keys,—said fall board being carried by the first-named board.

6. A case for player grand pianos having 15 side walls, vertical panel boards extending from the side walls toward the center; roll holders between the inner ends of the panel boards; a movable cover board depending in front of the roll holders and vertical 20 panel boards, and a fall board pivoted to the cover board for covering the keys and movable with the cover board.

7. A case for a player grand piano having side walls, rigid panel boards extending 25 in a crosswise direction from the side walls and being separated at the center; roll holders between the separated inner ends of the rigid panel boards; a cover board extending between the side walls and depending in 30 front of the panel boards and roll holders; a fall board pivoted to the cover board and foldable up against the cover board to expose the keys and means for pivotally sustaining the cover board to permit it and the 35 fall board to be swung up above the roll holders.

8. A case for a player grand piano having upper and lower roll boxes for the music rolls; a movable cover board pivotally sustained from above the said roll boxes and depending in front of the latter and a fall 40 board for the keys which is carried by the cover board and movable with the latter to uncover the roll boxes.

45 9. A case for a player grand piano having upper and lower roll boxes for the music rolls; a desk above the boxes; a cover board normally sustained in front of the boxes to conceal the latter and movable upwardly 50 and over the desk to expose the boxes, and a fall board for the keys,—said fall board being carried by the cover board and movable with the latter.

10. A case for a player grand piano having 55 side walls, upper and lower roll boxes for the music rolls; a rigid panel board ex-

tending from the roll boxes to the side walls; a desk above the boxes; a cover board pivotally sustained so as to swing over the desk and normally depending in front of the 60 roll boxes and rigid panel boards and a fall board pivoted to the cover board so as to swing up against the latter to expose the keys and then move with the cover board over the desk to expose the roll boxes. 65

11. A case for a player grand piano having side walls, upper and lower roll boxes; a desk above the boxes and said desk having a pivoted music rack; a cover board depending in front of the roll boxes; a fall board 70 pivotedly carried by the cover board and means above the roll boxes for pivotally carrying the cover board and fall board to swing them up and over the desk and music rack whereby to expose the roll boxes. 75

12. A case for a player grand piano having side walls, upper and lower roll boxes for the music rolls; rigid panel boards extending from the ends of the roll boxes to the side walls; a cover board depending in 80 front of both rigid panel boards and both roll boxes and extending between the side walls; a key fall board pivoted to the cover board and means at each end of the cover board for pivotally sustaining the latter. 85

13. A case for a player grand piano having side walls, upper and lower roll boxes for the music rolls; a desk above the roll boxes; pivoted arms at the opposite ends of the desk and projecting in front of the latter; a cover board carried by said pivoted arms and depending in front of the roll boxes and a fall board pivoted to the cover board to move independently of and also with the cover board. 95

14. A case for a player grand piano having side walls, upper and lower roll boxes for the music rolls; a desk above the roll boxes; a hinge strip at the front of the desk and over the upper roll box; a cover board 100 depending in front of and concealing the roll boxes; a key fall board carried by the cover board and means for pivotally sustaining the cover board to permit it and the fall board to be swung up over the desk. 105

In testimony whereof I affix my signature in presence of two witnesses.

JAMES P. CAULFIELD.
